(57) **CLAIM**

The ornamental design for an air conditioning apparatus, as shown and described.

DESCRIPTION

FIG. 1 is an upper perspective view of a design of an air conditioning apparatus;

FIG. 2 is a left side elevation view of the design of FIG. 1, the unshown opposite, right side being a mirror image;

FIG. 3 is a lower perspective view of the design of FIG. 1;

FIG. 4 is a rear elevation view of the design of FIG. 1;

FIG. 5 is a front elevation view of the design of FIG. 1;

FIG. 6 is a top plan view of the design of FIG. 1; and,

FIG. 7 is a bottom plan view of the design of FIG. 1.

The broken lines in the drawings illustrate portions of the air conditioning apparatus which form no part of the claimed design.
